(57) CLAIM

The ornamental design for a filter cover for a floor care appliance, as shown and described.

DESCRIPTION

FIG. 1 is a front perspective view of a filter cover for a floor care appliance showing my new design;

FIG. 2 is a front view thereof;

FIG. 3 is a right side view thereof; and,

FIG. 4 is a left side view thereof.

The portions shown in dashed lines are shown for illustrative purposes only and form no part of the claimed design.
